UNITED STATES PATENT OFFICE.

EDWARD C. BROADWELL AND JOHN A. LYONS, OF CHICAGO, ILLINOIS.

LAMP.

No. 929,280.

Specification of Letters Patent.

Patented July 27, 1909.

Application filed March 18, 1905. Serial No. 250,740.

To all whom it may concern:

Be it known that we, EDWARD C. BROADWELL and JOHN A. LYONS, citizens of the United States, and residents of the city of Chicago, in the county of Cook and State of Illinois, have invented certain new and useful Improvements in Lamps; and we do hereby declare that the following is a full, clear, and exact description of the same, reference being had to the accompanying drawings, and to the letters of reference marked thereon, which form a part of this specification.

This invention relates to that class of electric lamps known as incandescent and glow lamps.

Heretofore in all lamps in which the resistance of a filament causes the same to become heated to incandescence, great difficulty has been experienced in providing a filament or rod of sufficiently durable or lasting qualities to stand the high temperature necessary to satisfactorily serve the purpose for which intended.

The object of this invention is to provide a cheap and efficient metallic filament or rod for the use in glow or incandescent lamps in lieu of the usual filaments of carbon or other material.

It is also an object of the invention to afford in connection with a metallic or partly metallic filament or rod adapted to be heated to incandescence a mantle of suitable material to enhance the light efficiency of the lamp.

The invention consists in the matters hereinafter described and more fully pointed out and defined in the appended claims.

In the drawings: Figure 1 is a longitudinal section of a lamp embodying one form of our invention. Fig. 2 is an enlarged fragmentary view of the conductors, filament and a mantle therefor. Fig. 3 is a similar view of a lamp in which the filament or rod is differently supported. Fig. 4 is an enlarged fragmentary view of the conductors and the filament showing a mantle in place. Fig. 5 is a similar view with the mantle omitted. Fig. 6 is a longitudinal section of the mantle.

As shown in the drawings: referring first to Figs. 1 and 2, A and A' are screw plugs of porcelain or other suitable non-conducting material which, as shown, are connected by and close the ends of a glass or other transparent glow tube B. Extending axially into the tube through the plugs A and

A' are conductors C and C' which may be of copper or any suitable conducting material of sufficient size to conduct the current without becoming unduly heated. Each of said rods is provided on its outer end with a metallic contact plate a and a' respectively, adapted to afford the connection when the plugs are screwed into the sockets in circuit. Connecting the inner ends of said rods C and C' is a filament or rod c² of any configuration containing metallic chromium. Said rod or filament may be supported on conductors C and C' in longitudinal alignment indicated in Fig. 2 or if preferred may be supported at its ends upon approximately parallel conductors C² and C³ which extend into and through a plug A² as is usual with incandescent lamps, one of said conductors connecting with the outer metallic screw threaded shell a² and the other of said conductors extending centrally through the plug and connecting with a conducting plate c⁴. In this construction, a transparent bulb or globe B' surrounds the conductors and is hermetically sealed by its connection with the plug in the usual or any desired manner.

The depending ends of the conductors C² and C³ are connected by means of a filament c² such as before described. An incandescent mantle D or D' may be supported to inclose or partly inclose the filaments upon a rod d of copper, platinum or other suitable material carried on one of the screw plugs A' or may be supported on the filament.

Preferably the rod or filament is used in porous condition, there being alloyed or chemically combined with the chromium in any quantity consistent with maintenance of high fusion point, any chemical element such as manganese which enhances the electrical resistivity as well as also a volatile inorganic chemical element such as arsenic or a compound thereof in proportion of say: 20% more or less, which latter volatile element or compound will, upon dissipation by intense heat, leave the chromium rod or filament porous yet continuous throughout. The rod is then preferably coated with such earth oxids as are able to increase the refrangibility of the radiant energy as for example the oxids used in the mantle of Welsbach. In event of the earths used to increase the intensity of illumination being nonreducible by glowing metallic chromium, said earths can be forced into the pores on

the surface of the rod by subjecting the rod embedded in such earths to pressure but since efficiency of temperature rise for given heat increment varies inversely as the specific 5 heat of the oxid, used and since unfortunately those oxids having the lowest specific heats are easily decomposed by glowing chromium, a loosely fitting hollow concentric cylindric covering or mantle D or D' 10 preferably not touching the incandescent chromium rod or filament or touching it only at the ends of said mantle is the best method now conceived.

In carrying out our invention, slender rods 15 of zinc chromium, or titanium alloy, are raised to high incandescence in an inert gas such as hydrogen whereby the zinc is boiled away leaving a porous rod of much greater mechanical strength than the carbon filament or rods heretofore in vogue. This rod being in itself a glower may be used bare and may be subjected to sufficient pressure to compress it into a rod of continuous 20 solidity throughout in place of porous, provided its electrical resistance be made high enough by alloying with it a sufficient quantity of a metal having a tendency to form acid oxids or metallic acids for example molybdenum, tungsten or manganese 25 30 but as shown, we have incased the rod with a snug yet loosely fitting mantle capable of incandescence.

Fundamentally our invention affords an electric path of metallic chromium or its alloys which may be bare, or porous and filled 35

and covered with such oxids as by their low specific heat and high fusion point are able to raise the luminescence of a contiguous glowing body by the transformation of units or quantity of heat into light.

The bulb or transparent tube or envelop either is vacuous or contains an inert gas under diminished pressure.

Obviously the lamps may be of any preferred construction and the filaments may 45 be connected in circuit in any suitable manner.

We claim as our invention:

1. The combination with an electric light filament comprising a thread of porous 50 metallic chromium and metallic oxids contained within the pores of said thread of a mantle of earth oxids inclosing but out of contact with the same.

2. The combination with an electric light 55 filament comprising a porous rod of chromium of suitable metallic oxids having a high fusing point contained within the pores of the rod, said metallic oxids capable of raising the luminescence of the filament and a 60 mantle of earth oxids inclosing the same.

In testimony whereof we have hereunto subscribed our names in the presence of two subscribing witnesses.

EDWARD C. BROADWELL.
JOHN A. LYONS.
